Primary Examiner — Marie D. Fast Horse*Assistant Examiner* — Altaira J Swangin(74) *Attorney, Agent, or Firm* — CKC & Partners Co., LLC(57) **CLAIM**

The ornamental design for a case panel as shown and described.

DESCRIPTION

FIG. 1 is a front, top, right perspective view of a case panel, showing the claimed design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged view of portion 7 of FIG. 1 thereof;

FIG. 8 is an enlarged view of portion 8 of FIG. 1 thereof; and,

FIG. 9 is an enlarged view of portion 9 of FIG. 1 thereof. The dot-dash broken lines in the drawings represent the extents of the enlarged detail views and form no part of the claimed design.
